(57) **CLAIM**

I claim the ornamental design for the accessories belt, as shown and described.

DESCRIPTION

FIG. 1 is a left side, top, and front perspective view of the accessories belt, in accordance with the present invention, wherein the accessories belt is shown in a flat state; FIG. 2 is a top plan view of the accessories belt in the flat state;

FIG. 3 is a bottom plan view of the accessories belt in the flat state;

FIG. 4 is a left side elevational view of the accessories belt in the flat state;

FIG. 5 is a right-side elevational view of the accessories belt in the flat state;

FIG. 6 is a rear elevation view of the accessories belt in the flat state;

FIG. 7 is a front elevational view of the accessories belt apparatus in the flat state;

FIG. 8 is a perspective view of the accessories belt shown in a state of use; and

FIG. 9 is a perspective view of the accessories belt shown in a state of use.

The dash-dash broken lines depict stitching that forms no part of the claimed design.

The long dash-short dash broken lines depict environmental subject matter that forms no part of the claimed design.

1 Claim, 8 Drawing Sheets
